A. S. ROBINSON.

TUBE EXPANDER.

APPLICATION FILED FEB. 8, 1919.

Patented June 3, 1919.

Inventor

A. S. Robinson

By Watson E. Coleman
Attorney

UNITED STATES PATENT OFFICE.

ALBERT S. ROBINSON, OF WESTON, COLORADO.

TUBE-EXPANDER.

1,305,669.

Specification of Letters Patent. Patented June 3, 1919.

Application filed February 8, 1919. Serial No. 275,819.

To all whom it may concern:

Be it known that I, ALBERT S. ROBINSON, a citizen of the United States, residing at Weston, in the county of Las Animas and 5 State of Colorado, have invented certain new and useful Improvements in Tube-Expanders, of which the following is a specification, reference being had to the accompanying drawings.

10 This invention relates to certain improvements in tube expanders, and it is an object of the invention to provide a device of this general character with novel and improved means whereby the expander may be properly engaged within a tube to be worked without the necessity of the operator entering within a firebox, and also whereby the necessity of extinguishing the fire or reducing the steam pressure within the boiler is 15 unnecessary.

15 The invention consists in the details of construction and in the combination and arrangement of the several parts of my improved device whereby certain important 20 advantages are attained and the device rendered simpler, less expensive and otherwise more convenient and advantageous for use, as will be hereinafter more fully set forth.

25 The novel features of my invention will hereinafter be definitely claimed.

30 In order that my invention may be the better understood, I will now proceed to describe the same with reference to the accompanying drawings, wherein:

35 Figure 1 is a view in side elevation of a tube expander constructed in accordance with an embodiment of my invention, the coacting part of a boiler structure being 40 diagrammatically indicated by dotted lines; and

45 Fig. 2 is a view partly in elevation and partly in section of my improved device with the elongated rod shown in position to operate as a hammer.

50 As disclosed in the accompanying drawings, 1 denotes an elongated tubular member open at both ends and which is of a length to be readily inserted through the door of a firebox and to closely approach the boiler flue sheet.

E denotes a tube expander of any ordinary or preferred type, and which includes

a mandrel 2 extending within an end portion of the elongated member 1 and suitably 55 secured thereto as at 3. The opposite end portion of the member 1 is provided with laterally directed handle members 4 whereby rotary movement may be imparted to the member 1 with a resultant rotation of the 60 expander E when it is desired to roll the tube in place.

R denotes an elongated rod which is readily insertible within the member 1 through its outer end, and which rod R serves as a 65 hammer whereby requisite impact may be imposed upon the mandrel 2 of the expander E to effect the requisite expanding operation when said expander E is properly engaged within a tube.

70 An end portion of the rod R is provided with a laterally directed saddle or yoke 5 which is adapted to be engaged with the mandrel 2 of the expander in order to facilitate the proper application of said expander 75 E within the end portion of a tube to be worked. The rod R is of a length to permit the expander E to be properly engaged within a tube without the necessity of the operator entering within the firebox of a 80 boiler and, as has been fully demonstrated in practice the rod R can be employed to properly position the expander E without the necessity of the fire being extinguished or the pressure within the boiler being reduced.

85 From the foregoing description, it is thought to be obvious that a tube expander constructed in accordance with my invention is particularly well adapted for use by 90 reason of the convenience and facility with which it may be assembled and operated and it will also be obvious that my invention is susceptible of some change and modification without departing from the principles and 95 spirit thereof, and for this reason I do not wish to be understood as limiting myself to the precise arrangement and formation of the several parts herein shown in carrying out my invention in practice except as hereinafter claimed.

I claim:

100 In combination, an elongated tubular member, an expander including a mandrel extending within an end portion of the tubular member and secured thereto, and an 105

elongated rod insertible through the opposite end portion of the tubular member and adapted to serve as a hammer to impose requisite impact upon the mandrel of the 5 expander to effect an expansion operation, an end portion of said rod being provided with a saddle to receive the mandrel of the expander whereby the rod may be employed

to facilitate the fitting of the expander within a tube.

In testimony whereof I hereunto affix my signature in the presence of two witnesses.

ALBERT S. ROBINSON.

Witnesses:

JESUS M. MARTINEZ,
IRA B. GALE.
